TAPESTRY, EMBROIDERY OR RUG FRAME

Application filed June 8, 1928. Serial No. 283,955.

My invention relates to an improved frame for use in making embroidered articles, "hooked" rugs, and tapestries.

Hooked rugs are at present made by hand by working wool or yarn through a backing, such as a piece of burlap, stretched on a frame.

The backing or piece of burlap bears a pattern which is followed by the worker who uses a special needle to carry the yarn through the meshes of the burlap to form small loops. After a few rows of loops have been stitched, the loops are cut, which necessitates alternately working on opposite sides of the burlap and requires repeated turning over of the frame and burlap or backing carried thereby, the stitching being carried on one side of the backing, and cutting on the other side thereof.

Usually, the frame is arranged with one end resting on the lap of the worker and the other end being supported by a table. The worker stitches the material on the frame in front of him, then tilts the frame over to bring the other side up so that the loops may be cut.

This operation is tiresome and inconvenient as the work is carried on at arm's length and is inconveniently distant for cutting the loops.

For the foregoing reasons, no needle work frames for use in making hooked rugs have been found to be satisfactory and the common procedure is to turn and twist the frame by hand, according to the requirements of the work as it progresses. Furthermore, some of the rugs, being of large size and heavy, considerable muscular effort is necessary in order to handle the frame.

While more difficulty has been experienced in the making of hooked rugs than with embroidery, nevertheless somewhat the same objections prevail in regard to the ordinary hand embroidery frame as to those used for making rugs.

The object of the present invention is to provide an improved tapestry, embroidery or rug frame, particularly adapted for the easy and convenient handling of hooked rugs, but also well adapted for tapestry and em-

broidery work, which will enable a piece of tapestry, embroidery or a rug of any of the usual sizes, to be held in position to enable the work to be carried on conveniently and easily, provide for swinging of the work around to any position or reverse it or to enable the greater length of the piece to be arranged either vertically or horizontally and, with large rugs, to provide for accommodating the extra bulk of material which is necessarily rolled up on the edges of the frame.

The invention comprises a frame for holding the piece of tapestry, embroidery or the backing for the rug, a supporting frame capable of adjustment to accommodate the piece of backing with its greater length arranged laterally, instead of vertically, and to accommodate the rolled-up parts of rugs or pieces of good size, means for mounting the adjustable frame and supporting frame so that they may be swung laterally as a unit, means for mounting the rug or embroidery frame so that it can be swung on a horizontal axis to reverse it, and other novel features and combinations appearing more fully hereinafter.

In the accompanying drawings:

Figure 1 is a front elevation, dotted lines showing how either or both of the adjustable parts of the main frame may be extended and the rug frame arranged with its greater length horizontal;

Fig. 2 is an enlarged front elevation, partly in section, showing the mountings for the frames and the adjustable features thereof;

Fig. 3 is a section on the line 3—3, Fig. 2; and

Fig. 4 is a detail plan view of the horizontal piece or section of the adjustable frame.

The supporting base or pedestal comprises the enlarged base piece 1, the pedestal 2, and the turn table cap 3, there being provided a pivot or spindle 4 which extends upwardly beyond the cap or turn table 3 through a hole 5 in the horizontally arranged section 6 of the main frame so that the main frame is mounted to turn on the upper end of said spindle 4 as shown in Fig. 2, and the section 6 rests on the turn table 3 which receives the weight of the parts and of the piece of work.

carried thereby, thus relieving the spindle 4 of the weight.

The horizontal piece 6 is provided with a groove or channel 7 extending from one end to the other end thereof and has lateral holes 8 intersecting said channel. The base piece 9 of the section 6 is extended beyond the terminii of the channeled part of said section as shown at 10, Fig. 4, to serve as a support for the upright pieces or sections 11 of the main frame.

The upright pieces or sections 11 abut the squared ends of the sections 6 and they rest upon the extended parts 10. Carried by the upright sections 11 are horizontally arranged bars 13 which are received in the channel 7 and are provided with several lateral holes 14.

Removable pins 15 which are inserted through holes 8 and through selected ones of the holes 14, are adapted to lock the upright sections 11 in any position of lateral adjustment to which they may be moved. For instance, in Fig. 1, the sections 11 are shown in full lines as abutting the ends of the sections 6 and as resting on the extensions which will be the ordinary position for working the ordinary sizes of embroidery, tapestry or rugs. In dotted lines, Fig. 1, illustration is given of how either or both of the upright sections 11 may be adjusted laterally to accommodate large pieces of tapestry, embroidery or rug backings, as will now appear.

The rug or embroidery carrying frame is shown at 16, being a rectangular wooden frame adapted to fit between the upright sections 11 and to be pivotally and reversibly suspended by them. This frame may be arranged vertically as shown in Figs. 1 and 2, in full lines, or one or both of the uprights 11 may be shifted farther apart so that the frame 16 may be arranged with its greater length disposed laterally as shown by dotted lines.

The frame 16 is supported from rods 17 which project toward each other from the uprights 11, said rods being securely held by the uprights at one end as shown at 18. A tube 19 receives the ends of the rods 17 and, with them, constitutes a rigid, extensible support for the frame 16 whether it be arranged as shown in full lines or as in dotted lines. The frame is suspended from the rods by screw eyes 20, or hooks.

The backing for the hooked rug, or the piece which is to be embroidered, is secured to the frame 16 in any suitable manner, not shown.

The worker sits in front of the frame and can quickly, easily, and conveniently reverse the frame or base by turning it over on the pivot rods 17, or, turn the entire frame 6 and 11 laterally, swinging with said main frame the frame 16, or, either frame

may be turned to any limited extent desired to facilitate the work.

The complete frame, when not in use, may serve as a screen of attractive appearance because it carries the work on the frame 16. 70

What I claim is:

1. A work-frame for fabric, comprising a main frame having uprights which are adjustable laterally in relation to each other, and a rectangular fabric-carrying frame mounted on a horizontal axis on said uprights and located between them and adapted for complete swinging reversal on the horizontal axis, said frame being provided with means on all of its four sides whereby it may be mounted on said horizontal axis between the uprights to swing or reverse as aforesaid when arranged with either its lesser or its greater length disposed horizontally. 85

2. A work-frame for fabric, comprising a supporting pedestal, a main frame supported thereby having laterally adjustable uprights which may be shifted toward or away from each other on the main frame, a fabric-carrying frame, an extensible pivotal horizontal mounting for said fabric-carrying frame comprising relatively longitudinally shiftable overlapping cooperating members, and means on the sides of the fabric-carrying frame for supporting the fabric-carrying frame from said uprights, with either its greater or lesser length pivoted on the horizontal mounting, whereby said fabric-carrying frame is mounted between the uprights 100 for swinging about a horizontal axis when arranged with either its lesser or greater length disposed horizontally. 90

3. In a work-frame for fabric, the combination with a supporting pedestal, of a main frame comprising a horizontally arranged section supported by the pedestal, and relatively adjustable upright sections which have lateral extensions adapted to be slid lengthwise of the horizontally arranged section and secured to the horizontally arranged section at different points of their length, affording means for disposing the upright sections at different distances apart, horizontally arranged pivot rods operatively connected to each other and carried by the extensible uprights, and a fabric-carrying frame having means on the sides thereof for pivotally mounting the same on said rods between the uprights whereby it is adapted to be arranged with either its lesser or its greater length disposed horizontally and for reversal or change of position. 110

In testimony whereof I affix my signature. 125
THOMAS R. LOMBARD.
